[57] CLAIM

The ornamental design for a combined writing instrument, stamp and ink pad, as shown and described.

DESCRIPTION

FIG. 1 is a right front perspective view of a combined writing instrument, stamp and ink pad showing our new design with the cap member in a stored position; FIG. 2 is a front elevational view in an exploded condition;

FIG. 3 is a left side elevational view with the cap member in a closed position;

FIG. 4 is a rear elevational view of FIG. 3;

FIG. 5 is a top plan view of FIG. 3; and,

FIG. 6 is a bottom plan view of FIG. 3;

The hand depicted by means of broken lines in FIG. 1 is for illustrative purposes only and forms no part of the claimed design.

FIG. 1

FIG. 2

FIG. 3
